UNITED STATES PATENT OFFICE.

ELLSWORTH A. HAWTHORNE, OF BRIDGEPORT, CONNECTICUT.

DESIGN FOR A MIRRORSCOPE.

51,556.

Specification for Design.

Patented Dec. 11, 1917.

Application filed July 9, 1917. Serial No. 179,567. Term of patent 14 years.

To all whom it may concern:

Be it known that I, ELLSWORTH A. HAWTHORNE, a citizen of the United States, and a resident of Bridgeport, in the county of Fairfield and State of Connecticut, have invented a new, original, and ornamental Design for a Mirrorscope, of which the following description, in connection with the accompanying drawings, is a specification.

In the drawings:

Figure 1 is a rear elevation;

Fig. 2 is a side elevation, partly in vertical section; and

Fig. 3 is a front elevation of a mirrorscope showing my new design.

I claim—

The ornamental design for a mirrorscope, as shown.

In testimony whereof, I have signed my name to this specification.

ELLSWORTH A. HAWTHORNE.
